(57) **CLAIM**

The ornamental design for a dual motor transom for pontoon boats, as shown and described.

DESCRIPTION

FIG. 1 is a front top left side perspective view of the dual motor transom for pontoon boats.

FIG. 2 is a back top side perspective view of the dual motor transom.

FIG. 3 is back view of the dual motor transom.

FIG. 4 is a front view of the dual motor transom.

FIG. 5 is top view of the dual motor transom.

FIG. 6 is a bottom view of the dual motor transom.

FIG. 7 is a right side view of the dual motor transom.

FIG. 8 is a left side view of the dual motor transom.

FIG. 9 is a front perspective view of the dual motor transom for pontoon boats which is attached to a pontoon boat; and, FIG. 10 is a front perspective view of the dual motor transom for pontoon boats which is attached to a pontoon boat and with dual outboard motors being attached thereto.

The dashed broken lines illustrate portions of the dual motor transom for pontoon boats and environmental background that form no part of the claimed design. The dot-dash lines in FIGS. 9 and 10 illustrate the boundaries of the environmental background and form no part of the claimed design.
